[57] CLAIM

The ornamental design for a specimen cup holder with breakaway handle, as shown and described.

DESCRIPTION

FIG. 1 is a top plan view of a specimen cup holder with breakaway handle showing our new design;

FIG. 2 is a bottom plan view thereof;

FIG. 3 is a side elevational view thereof, the opposite side elevational view being identical thereto;

FIG. 4 is a rear elevational view thereof;

FIG. 5 is a front elevational view thereof;

FIG. 6 is a perspective view thereof, wherein the handle has been broken away;

FIG. 7 is a side elevational view thereof, the opposite side elevational view being a mirror image thereof;

FIG. 8 is a top plan view thereof;

FIG. 9 is a bottom plan view thereof;

FIG. 10 is a rear elevational view thereof; and,

FIG. 11 is a front elevational view thereof.
